UNITED STATES PATENT OFFICE.

JOHN A. BARTHOLOMEW, OF CHICAGO, ILLINOIS.

MEDICINAL APPLICATOR AND SWAB.

982,232.

Specification of Letters Patent. Patented Jan. 24, 1911.

Application filed January 13, 1908. Serial No. 410,565.

To all whom it may concern:

Be it known that I, JOHN A. BARTHOLOMEW, a citizen of the United States, and a resident of the city of Chicago, county of Cook, and State of Illinois, have invented certain new and useful Improvements in Medicinal Applicators and Swabs; and I do hereby declare that the following is a full, clear, and exact description of the same, reference being had to the accompanying drawings, and to the letters of reference marked thereon, which form a part of this specification.

It is frequently important to apply in the various cavities of the body and head medicinal preparations, and it is, of course, important in such cases that the applicator be of such a nature as to preclude possibility of injury either because of the manner of its construction or because it is not readily made antiseptic.

With this in view, it is an object of my invention to afford an applicator and swab so constructed as to be easily sterilized without affecting the quality or utility thereof and of such material as to afford great resiliency and absorptive power.

It is a further object of the invention to afford a device of the class described in which any rigid portion thereof is entirely inclosed in a resilient, absorptive covering of such a nature, however, as to entirely prevent any such rigid portions being projected therethrough to cause injury.

The invention consists in the matters hereinafter described and more fully pointed out and defined in the appended claim.

In the drawings: Figure 1 is a side elevation of a device embodying my invention. Fig. 2 is a longitudinal section of the pad of the applicator. Fig. 3 is a section taken on line 4—4 of Fig. 2.

In said drawings: A represents the applicator pad or head which is constructed of sponge rubber and shaped to afford a comparatively long and slender pad resembling in shape the frustum of a cone and having bases rounded. Through the larger base thereof and forced inwardly of the pad approximately to or beyond the center is the handle A'. This may be shaped to suit the requirements of the user. Usually, however, and preferably, it is cylindric to enable the handle to be rolled between the fingers or hands, thereby rapidly rotating the applicator in the cavity that is being treated or

cleansed. The handle may be inserted in the pad in any suitable manner. Conveniently some sharp pointed instrument of the nature of a speculum may be pressed into the larger base of the pad and the blades dilated to permit the handle to be pressed into place. The speculum blades are then removed and the natural resiliency of the rubber firmly binds the pad upon the handle. This binding effect, may, of course, be increased by roughening that portion of the handle which is inserted into the pad or by providing on the inner end of the handle an enlarged head a behind which the rubber in contracting, firmly engages, holding the pad from removal.

Of course, if desired, the pad may be trimmed after the insertion of the handle therein and of course, the proportions of the pad may vary depending upon the orifice the same is adapted for.

The operation is as follows: The pad is first thoroughly sterilized by any approved method and owing to the material with which it is constructed, is not capable of being injured by such sterilizations, and owing to the porosity of the pad the sterilizing agent finds access to all parts thereof. After sterilization the applicator is soaked or impregnated in the medicine to be applied and again the porosity of the applicator enables a large quantity of the medicament to be taken up in the pores thereof. The pad is then inserted by means of the handle into the cavity to be cleansed and may, by rotation thereof, be brought into contact with all parts of the wall of the cavity, thus not only thoroughly cleansing the same but as well applying the medicament thereto.

Of course, the applicator may be used merely for cleansing purposes and for this purpose soap and water may be used instead of the medicament. This is particularly important owing to the desirability of protecting the lungs from the soot that otherwise accumulates in the nose by removing such material frequently. This can, of course, be easily accomplished by the implement herein shown and described.

Of course, details of construction may be varied without departing from the principles of this invention.

I claim as my invention:

An applicator comprising a pad of sponge rubber tapered from one end to the other and rounded at its outer end, an axial bore

in the pad enlarged at its inner end providing a shoulder and a stem provided with a tapered head adapted to spread the pad to enter the bore and having an abrupt shoulder to engage the shoulder at the inner end of the bore in the pad to prevent retraction thereof.

In testimony whereof I have hereunto subscribed my name in the presence of two subscribing witnesses.

JOHN A. BARTHOLOMEW.
